UNITED STATES PATENT OFFICE.

NICHOLAS RIPPENBEIN, OF PERTH AMBOY, NEW JERSEY.

DISPLAY CONTAINER.

Application filed July 26, 1923. Serial No. 653,859.

To all whom it may concern:

Be it known that I, NICHOLAS RIPPENBEIN, a citizen of the United States, and a resident of Perth Amboy, in the county of 5 Middlesex and State of New Jersey, have invented certain new and useful Improvements in Display Containers, of which the following is a specification.

My invention relates to improvements in 10 the class of containers or boxes having lids or covers hinged thereto, adapted to fold over the open side of the container and to remain in an upward position for display of the goods within the container and the 15 display matter on the lid.

The object of my invention is to provide 20 a container of the class referred to with means to retain the lid or cover in an upwardly and preferably rearwardly inclined position so that it will neither fall too far backwardly nor have a tendency to fall forwardly when opened for display, and 25 whereby the lid may be folded over the open side of the box to conceal and protect the contents of it.

My invention comprises novel details of 30 improvements that will be more fully hereinafter set forth and then pointed out in the claims.

Reference is to be had to the accompanying 35 drawings forming part hereof, wherein—

Fig. 1 is a side elevation of a container 40 embodying my invention, showing the lid in display position;

Fig. 2 is a perspective view of the container;

Fig. 3 is a plan view of the container 45 showing the lid closed;

Fig. 4 illustrates a blank for the container of Figs. 1, 2 and 3;

Fig. 5 is a perspective view of a modification and;

Fig. 6 illustrates a blank for the container 50 of Fig. 5.

Similar numerals of reference indicate 55 corresponding parts in the several views.

The main body of the container is indicated at 1, shown comprising a bottom 2, a back wall 3, a front wall 4 and side walls 5. At 6, is a lid or cover shown hinged to the outer edge of back wall 3, adapted to fold over the opening of the container and to extend upwardly for display. While the 60 lid 6 may be hinged to the back wall 3 in any desired way, I have shown the lid

hinged to the back wall by means of a score line at 7 in the material of the blank for the container, providing a transverse hinge.

While the main body 1 of the container 60 may be made in any desired or well known way, I have shown the same in Figs. 1 to 4 as formed from a single piece of material as illustrated in the blank in Fig. 4 having spaced score lines 8 and 9 along which the 65 back wall 3 and the front wall 4 respectively may be folded to be set up, said blank being shown provided with spaced score lines 10, along which the side walls 5 are attached. The back wall 3 is shown provided with side extensions 11 and the front wall 4 is shown provided with side extensions 12, foldable along the score lines 70 10, whereby, when the sides are set up, the extensions 11 and 12 may be secured 75 to the side walls 5 by glue or other suitable means.

To retain the lid 6 in a display position I provide bracing webs 13 that connect the inner or lower portions of the sides of the 80 lid with the adjacent complementary extensions 11, whereby, when the lid is opened, said bracing webs will retain the lid in a display position. In order to permit the lid to be retained in an upwardly and some- 85

what rearwardly inclined position for display purposes, the bracing webs 13 are hingedly connected with the respective adjacent parts of the lid by lines 14 which are oblique to the hinge 7, providing primary hinges, and said bracing webs extend from the adjacent upper edges of the extensions 11, along the extensions 7^a of the 90 score line 7 of the blank, providing secondary hinges. It will be observed that the 95

primary hinges 14 together with the secondary hinges 7^a form obtuse angles, whereby the lid may extend in an upwardly and rearwardly inclined position respecting the body of the container, and the primary 100 hinges 14 lie between the planes of the side walls of the container, as distinguished from prior constructions known to me, where lids for containers have been provided with bracing webs attached to the 105 sides of the lids on score lines that are rectangular to the upper edges of the back walls, and where the bracing webs are in the planes of the side walls of the container, whereby the lid cannot assume a position rearward of a perpendicular respecting the container. It will also be observed 110

that the bracing webs in my container lie in planes oblique to the planes of the adjacent side walls, of the back wall and of the lid, when the bracing webs are fully extended with the lid in an upwardly and rearwardly inclined position and it will be also observed that the primary hinges are convergent. In order that the lid 6 may be folded over the open side of the container, I provide the bracing webs 13 with score lines at 15 extending from the angles formed at the junctions of the score lines 7 and 14. The score lines 15 are shown at angles of 45 degrees with respect to the hinge score lines 14. The construction described enables the bracing webs 13 to be folded inwardly when the lid is to be closed.

It will be observed that the outer edges 13^a extend into the body of the lid where 20 such edges are detached from the lid by cuts at 16 in the lid.

In the form of my invention shown in Figs. 5 and 6, the side walls 5 comprise two members 5^a, 5^b each, hinged along the score lines 5^c, to fold inwardly over and retain the rectangular side extensions 11, to which the bracing webs are hinged by the secondary hinges at 7^a, the members 5^b, having lips 17, retained by tongues 18, cut out of the bottom 30. 2. In this form, the container is of the unglued variety. My improvements may be applied in any other desired form of container having its front, back and side walls attached together in any other well known 35 way.

By means of my improvements, I am enabled to provide a container, preferably of the one piece variety, whereby the lid may be retained by the bracing webs in a definite 40 upwardly and rearwardly inclined position to permit the display matter on the lid to be readily visible. My improvements are inexpensive to manufacture and enable the lid to be set up for display by merely raising 45 it from the container without requiring any adjustment of parts, since the oblique relation of the bracing webs to the adjacent parts of the container cause said webs to automatically locate themselves in their 50 proper relative positions upon raising the lid.

It will be understood that with the extensions 11 secured to or retained by the side walls, the bracing webs are thereby secured 55 to and extend from said side walls.

Having now described my invention, what I claim is:

1. A display container having a lid hinged thereto and a bracing web hinged to the

container and to the lid, the hinge between 60 the lid and the bracing web extending at an oblique angle to the hinge between the lid and the container.

2. A display container as set forth in claim 1 in which the bracing web is provided with a score line extending at an angle 65 to the hinge between the lid and the container.

3. A display container comprising a back wall, a pair of side walls, a transverse hinge 70 coinciding with said back wall's top edge, a lid joined to said back wall by means of said hinge, a bracing web hingedly connected with a lower side portion of said lid by means of a primary hinge, said primary 75 hinge being oblique to said transverse hinge, said bracing web being hingedly connected with an adjacent side wall by means of a secondary hinge coinciding with said side wall's upper edge.

4. A display container comprising a back wall, a pair of side walls, a transverse hinge coinciding with said back wall's upper edge, a lid joined to said back wall by means of said hinge, a bracing web hingedly connected with a lower side portion of said lid by means of a primary hinge and said bracing web being hingedly connected also with an adjacent side wall by means of a secondary hinge coinciding with said side wall's 80 upper edge, said primary hinge forming an obtuse angle with said secondary hinge.

5. A display container as set forth in claim 3, said bracing web lying in a plane oblique to the plane of said adjacent side 85 wall, when said bracing web is fully extended with said lid in an upwardly and rearwardly inclined position.

6. A display container as set forth in claim 4, said bracing web lying in a plane 100 oblique to the plane of said adjacent side wall, when said bracing web is fully extended with said lid in an upwardly and rearwardly inclined position.

7. A display container comprising a back 105 wall, a pair of side walls, a transverse hinge coinciding with said back wall's upper edge, a lid joined to said back wall by means of said hinge, a pair of bracing webs, each hingedly connected with a lower side portion of said lid by means of a primary hinge, said primary hinge being oblique to said transverse hinge, said bracing web being also hingedly connected with an adjacent 110 side wall by means of a secondary hinge coinciding with said side wall's upper edge.

NICHOLAS RIPPENBEIN.
